(57) **CLAIM**

The ornamental design for an auxiliary screen for spectacles, as shown and described.

DESCRIPTION

FIG. 1 is a front, right perspective view of an auxiliary screen for spectacles showing my new design;

FIG. 2 is a rear, right perspective view of the auxiliary screen for spectacles;

FIG. 3 is a front elevational view of the auxiliary screen for spectacles;

FIG. 4 is a right side view of the auxiliary screen for spectacles;

FIG. 5 is a left side view of the auxiliary screen for spectacles;

FIG. 6 is a top plan view of the auxiliary screen for spectacles;

FIG. 7 is a bottom plan view of the auxiliary screen for spectacles;

FIG. 8 is a rear elevational view of the auxiliary screen for spectacles;

FIG. 9 is a front, right perspective view of an auxiliary screen for spectacles showing my new design in use with spectacles;

FIG. 10 is a rear, right perspective view of the auxiliary screen for spectacles in use with spectacles;

FIG. 11 is a front elevational view of the auxiliary screen for spectacles in use with spectacles;

FIG. 12 is a right side view of the auxiliary screen for spectacles in use with spectacles;

FIG. 13 is a left side view of the auxiliary screen for spectacles in use with spectacles;

FIG. 14 is a top plan view of the auxiliary screen for spectacles in use with spectacles;

FIG. 15 is a bottom plan view of the auxiliary screen for spectacles in use with spectacles; and,

FIG. 16 is a rear elevational view of the auxiliary screen for spectacles in use with spectacles.

The broken line showing of the spectacles is for illustrative purposes only and forms no part of the claimed design.
